ATTACHMENT FOR HOLDING AND STIFFENING MERCHANTISE PACKAGES

Maurice Garbaty, Larchmont, N. Y.

Application November 30, 1939, Serial No. 306,864

4 Claims. (Cl. 206—41.2)

My invention relates to improvements of attachments for holding and stiffening merchandise packages as described in my former application Ser. No. 291,466, filed August 23, 1939.

The subject matter of my former invention is to provide a support for repeated use for holding and stiffening packages e. g. of paper, cardboard or the like which are discarded when emptied, comprising a rack conforming to the shape and the size of the package to be supported, a movable adapter able to fix the goods in a partially emptied package and a device capable to eject the goods from the supported package.

The new device according to this invention is an attachment especially appropriated for cigarette packages.

One object of the invention is to provide a support to be operated single-handed.

Another object of the invention is to provide an attachment which easily can be inserted between the inside of the wrapper of the package to be stiffened and the contents thereof, without damaging either the wrapper or the cigarettes.

Another object of the invention is to provide means of preventing a distortion of the inner part of the wrapper and of the cigarettes, when the adapter and the ejector are operated.

Another object of the invention is to provide special means of ejecting even the last cigarettes in the package without any difficulties.

In the accompanying drawing I have shown for purposes of illustration a form which the invention may assume in practice.

In the drawing:

Fig. 1 is a perspective view of the attachment.

Fig. 2 is a horizontal sectional view through the adapter taken at the line II—II of Fig. 1.

Fig. 3 is a vertical sectional view taken at line III—III of Fig. 1.

Fig. 4 is a fragmentary view of the upper end of the ejector-spring.

Fig. 5 is a top plan of a cigarette package, showing the arrangement of cigarettes and, in section, the relative positions of adapter and ejector.

The reference characters in the several figures denote like parts.

The attachment shown in the figures comprises a yoke 10 consisting of two legs 11 and 111 both pointing downwardly connected by a top-plate 14.

The shape and the size of the yoke conforms to the shape and the size of the package to be supported by the attachment.

The plate 14 is provided with a longitudinal slot 15. This slot has an enlarged portion 15a

suitably dimensioned to permit the proper discharge of the goods.

A gripper 16 rigidly connected with a downwardly disposed and movable plate or leg 18 slides through the slot 15 acting as an adapter which moves and firmly supports the goods in the package to which the attachment is to be applied.

The width of leg 18 is somewhat smaller than that of the legs 11 and 111 in order to avoid damages by engagement of the inner parts of the package wrapper with the moving adapter.

A vertical rib 18a is provided in the midst of the leg 18 preferably integral with the finger grip 16. To facilitate the movement of the adapter plate 18 the latter is guided by means of wings 18b in guiding channels 14a and 14b provided on both lengthsides of the top plate 14. These channels extend over leg 111 to facilitate discharge of the last cigarettes in the package supported by the attachment.

The legs 11, 111 and 18 are tapered at their extreme downward ends to facilitate the insertion of the device in the wrapper.

The leg 111 is provided with two channels 20 in which an ejector slide 21 is guided. The slide 21 ends on its upper part in a finger grip 21a shaped in a manner that the slide may be raised by putting the thumb under the grip.

The slide 21 is provided with a long levered spring 22. The upper part 22a is widened thus extending over the whole width of the slide 21. The slide positively cooperates with a stationary cam 23 so as to engage the goods on the upward stroke and to slip over the cigarettes without injuring them on the downward stroke.

To facilitate the one-handed operation of the ejector and the adapter, an outer wall 24 is provided. This wall is fastened on the top plate 14 and has to surround the outside of the package to which the device is to be attached.

The lower edges 24a of the casing 24 are bent outwardly to accommodate easy feeding in of the package wrapper between the wall 24 and the legs 11 and 111.

The device according to the invention may be used as follows:

The adapter 18 is set in close connection to leg 11 of the yoke 10 by moving the grip 16 accordingly, while the grip 21a is put down to insert the injector in its slide.

Now the device can be easily attached to a package of cigarettes which has been opened by removal of the top part of the wrapper.

Leg 11 with the adapter 18 on the one side

and leg 111 with slide 21 on the other side are inserted between the inside of the wrapper 13 and the cigarettes 12 whereas the casing 24 surrounds the outer part of the package to be supported. This feeding in is facilitated by the funnel-shaped form of the device.

The attachment can be operated by one hand: the grip 21^a of the ejector can be handled by the thumb and the grip 16 of the adapter by the forefinger of the same hand which rests closely on the casing 24. The discharge of cigarettes is performed by lifting the ejector 21 with the thumb.

When the first cigarettes are discharged and the ejector is put down again the adapter 18 is advanced by moving forward its grip 16. The rib 18^a secures the right position of the cigarettes even though the package is partially emptied.

It is possible to move the adapter so far that the last cigarettes may be discharged out of the package without difficulties, the channels 14^a and 14^b being extended.

I have described a preferred embodiment of my invention but it is understood that changes and omissions may be made without departing from the spirit of my invention.

What I claim is:

1. In a stiffening and holding device for cigarette packages comprising an adapter for the cigarettes and an ejector to be operated single-handed a U-shaped yoke conforming to the shape and size of the package to be stiffened consisting of a top plate to be placed on the top of an opened package of cigarettes, this top plate being provided with a discharge opening, and two downwardly directed flat plates integrally connected with said top plate at its opposite ends, said plates to be inserted in said package on its narrow sides between the wrapper and the cigarettes to exert pressure on the walls of said package; a downwardly directed movable adapter plate disposed in said yoke at the side of the top plate opposite to said discharge opening and to be moved parallelly to the legs of said yoke in the direction to said discharge opening by actuating a finger grip extending through a slot in the top plate, actuated by the forefinger of the operator; an ejector gliding up and down in guiding channels provided in the leg of said yoke located at said discharge opening, said slide being provided with a finger grip to be operated by the thumb of the same hand; an outer casing fastened to said top plate surrounding the outside of the package to be stiffened, adapted to support the hand of the operator.

2. In a stiffening and holding device for cigarette packages comprising an adapter for the cigarettes and an ejector to be operated single-handed a U-shaped yoke conforming to the shape and size of the package to be stiffened

consisting of a top plate to be placed on the top of an opened package of cigarettes, this top plate being provided with a discharge opening, and two downwardly directed flat plates integrally connected with said top plate at its opposite ends, said plates to be inserted in said package on its narrow sides between the wrapper and the cigarettes to exert pressure on the walls of said package; a downwardly directed movable adapter plate disposed in said yoke at the side of the top plate opposite to said discharge opening and to be moved parallelly to the legs of said yoke in the direction to said discharge opening by actuating a finger grip extending through a slot in the top plate, actuated by the forefinger of the operator; an ejector gliding up and down in guiding channels provided in the leg of said yoke located at said discharge opening, said slide being provided with a finger grip to be operated by the thumb of the same hand; an outer casing fastened to said top plate surrounding the outside of the package to be stiffened, said casing being broadened on its lower end to facilitate the adapting of the device to the cigarette package and to give support to the hand of the operator.

3. In a stiffening and holding device for cigarette packages a U-shaped yoke conforming to the shape and size of the package comprising a top plate being provided with a discharge opening and two downwardly directed legs connected with said top plate at its opposite ends, said plates to be inserted in said package on its narrow sides between the wrapper and the cigarettes to exert pressure on the walls of said package; a movable adapter plate disposed in said yoke and an ejector slide gliding up and down in guiding channels disposed in the leg of the stiffening yoke near said discharge opening, a long levered gripping spring being provided on the inner side of the slide, a stationary cam fixed to the leg adjacent the slide said spring being adapted to act as an ejector when passing said cam while moving upwardly.

4. In a stiffening device and holding device for cigarette packages a U-shaped yoke conforming to the shape and size of the package comprising a top plate being provided with a discharge opening and two downwardly directed legs connected with said top plate at its opposite ends, said plates to be inserted in said package on its narrow sides between the wrapper and the cigarettes to exert pressure on the walls of said package; a movable adapter plate of somewhat smaller width than those of the legs of said yoke, provided with a vertical middle rib securing the right position of the cigarettes, the adapter plate gliding horizontally by means of guiding channels in the top plate of the yoke extending over and above the yoke.

MAURICE GARBATY.
